BLUE FLAME BURNER

Herbert M. Reeves, Kankakee, Ill., assignor to
 Florence Stove Company, Gardner, Mass., a
 corporation of Massachusetts

Application July 2, 1938, Serial No. 217,159

4 Claims. (Cl. 126—44)

This invention has to do with burner construction, and is concerned more particularly with a burner construction of the blue flame type.

It is an object of the invention to provide an improved burner valve construction.

It is a further object to provide an improved burner mounting.

It is another object to provide a burner mounting comprising separate parts capable of speedy assembly.

A further object is to provide a construction in which a gang of burners is mounted on a common feed pipe.

It is also an object of the invention to provide a burner construction in which the valves are connected to a common feed pipe by relatively short tubes.

It is a further object of my invention to provide a connection between the fuel supply and the valve of a burner, whereby clogging of the fuel line by impurities in the fuel is substantially obviated.

Another object of the invention is to provide improved packing for a valve for fuel oil.

Another object is to provide a valve construction which is readily assembled with and separable from the cooperating burner and feed pipe.

It is also an object to provide a common mounting for one or more burners and associated valves.

A further object is to provide valve structures disposed entirely below the level of fuel in the tank.

Another object is to so mount a valve as to render the cylinder more easily accessible.

Further objects and advantages of the invention will appear as the description proceeds.

The invention will be understood upon reference to the following description and the accompanying drawing, in which:

Fig. 1 is a fragmentary front elevation of burner construction embodying features of my invention;

Fig. 2 is an enlarged section-elevation taken as indicated by the line 2—2 in Fig. 1;

Fig. 3 is an enlarged sectional view taken as indicated by the line 3—3 in Fig. 1;

Fig. 4 is an enlarged sectional view taken as indicated by the line 4—4 in Fig. 2; and

Fig. 5 is a reduced transverse sectional view taken as indicated by the line 5—5 in Fig. 1 and showing the assembled casing, burner and tank construction.

Referring now more particularly to the drawing, there is shown at 10 an oil, kerosene or other

liquid fuel tank suitably mounted, as adjacent the rear wall of the range casing 11. It could be mounted in back of the casing if desired. Disposed forwardly and within the casing 11 is a common feed pipe or manifold 12 whose ends are 5 plugged as at 13 and supported as on brackets 14, one of which appears fragmentarily. The pipe is connected to the tank as by a conduit 15 and nipple 16. Mounted on the pipe is a series or gang of burners indicated generally at 17. 10

Each burner includes any suitable cylinder 18 formed to rest on the shelf 19 of a burner bowl 20. The bowl 20 includes an annular channel 21 of U-shape in cross section and receiving an annular asbestos or other kinder 22. The bowl has 15 an inner plate portion 24 connected to the top of the inner side of the channel and affording secondary air openings 25. The plate 24 has a preferably central opening 26 through which extends the threaded shank 27 of a hook bolt 28 20 passing through a hole 29 in the bight 31 of a saddle 32. The bight terminates in seats 33 on which the bottom 34 of the bowl rests. The lower free ends of the arms 36 of the saddle are notched as at 37 to receive the upper side of the pipe 12. 25 The hook 40 of the bolt 28 extends around the bottom of the pipe 12 to engage the pipe in opposition to the saddle arms 36, and a nut 41 applied over the plate 24 and about the threaded shank 27 may be employed to firmly clamp the 30 saddle and hook against the pipe 12, thereby firmly clamping the bowl 19 on the saddle 32.

A valve structure embodying my invention for controlling the flow of fuel to the channel 21 is shown at 45 and comprises a casing 46 in which 35 is threadedly received a valve rod 47 surrounded by a packing gland, shown generally at 48, and employing a composition of asbestos and graphite, shown at 49, for preventing leakage. This material is particularly effective when, as here, fuel oil, kerosene or the like is used. The rod 47 has a flow control surface 51 engageable with a relatively stationary surface or edge 52, and between the surface 52 and the packing gland the 45 casing has an inlet branch 53. The casing 46 terminates outwardly beyond the surface 52 in an outlet 55 threadedly receiving the open end of a tube 56, the other end of said tube being 50 closed as shown at 57. The tube 56 has a hole 59 in its side adjacent the closed end thereof, and said tube is integrally united with the bottom of the channel 21, by soldering or otherwise as shown at 60, with the hole 59 in register with a hole 61 in said channel, whereby communication 55

is established between said tube and said channel.

- The valve rod 47 extends forwardly through a front panel or apron 65 of the casing and a handle 66 is mounted on the forward end of the rod forwardly of the panel 65. If desired, an escutcheon plate 67 also may be provided. A front door 68 may be hinged as at 69 to the frame and urged as by spring means 70 to closed position, and has an opening 71 to clear the handle 66 and permit the handle to be operated even when the door is in closed position, as shown in Fig. 2. A nut 72 or other suitable means may be employed to hold the handle and plate on the rod.
- In order that the valve may be fixedly supported, the apron 65 has an overhanging rearwardly extending flange 73 to which is spot-welded or otherwise suitably secured as at 74 a hanger 75 extending over the valve casing 46.
- A U-bracket 76 embracing the underside of the casing 46 has ears 77 bolted as at 78 or otherwise suitably fastened to the hanger 75.

A conduit 80 is detachably connected to the valve inlet branch 53 by means of a union 81 and to the feed pipe 12 by a coupling 82 so arranged as not to interfere with the hook 49. The valve 45 is elevated relative to the pipe 12, so that the ends of the conduit 80 are at different levels, thereby substantially obviating clogging by stagnation or accumulation of foreign matter from the liquid fuel.

Each valve 45 is disposed horizontally so that ample clearance is provided for inserting the hand to raise and lower the cylinder 18. The packing 49 enables the valve to operate even though it is entirely below the level of the fuel in the tank 10.

It will be seen from the foregoing that the burner, while adapted to be securely mounted on the pipe 12 by friction through the use of the bolt 28 and saddle 32, is additionally supported from the pipe through the valve 45 and conduit 80, and is still further supported independently of the pipe by the front panel or apron 65, whereby the burner is held rigidly in place.

The saddle 32 is preferably a loose piece unconnected to any other part, as is also the bolt 28. The tube 56 is detachably connected to the valve casing 46, the conduit 15 is detachably connected at 16 to the pipe 12, the conduit 80 is detachably connected to the pipe and valve casing and the valve casing is detachably connected to the hanger 75 and handle 66. Thus it is evident that the assembly and disassembly consume but a few moments, yet when the parts are con-

nected they operate efficiently as an integral whole.

It is evident that no special machining is required, the various members for the most part being of conventional design or in any event adapted to be constructed very economically.

Various other changes and modifications coming within the spirit of my invention will doubtless suggest themselves to those skilled in the art, and hence I do not wish to be limited to the specific forms shown or uses mentioned except to the extent indicated in the appended claims, which are to be interpreted as broadly as the state of the art will permit.

I claim:

1. In a fuel oil burner including a burner bowl and means providing a supply of fuel oil, a valve for connecting said means to said bowl, said valve comprising a valve rod and asbestos and graphite packing means for said rod.

2. In a range, a casing, a plurality of horizontally disposed burner bowls in said casing, a cylinder resting on each bowl, a fuel oil tank mounted on said casing, a valve for each bowl and disposed below the level of said oil, a feed pipe between and connected to said tank and said valves, each valve being disposed so as to leave the space in front of the associated cylinder clear for easy access of a hand to said cylinder, said valve having a handle, a front door hinged to said casing and having an opening adapted to receive said handle when said door is closed, whereby said handle may be operated when said door is closed, and means urging said door to its closed position.

3. In a range, a casing, a burner bowl in said casing, a cylinder on said bowl, a valve connected to said bowl and disposed so as to leave the space in front of the cylinder clear for easy access of a hand to said cylinder, said valve having a handle, a front door hinged to said casing and having an opening adapted to receive said handle when said door is closed, whereby said handle may be operated when said door is closed, and means urging said door to its closed position.

4. In a burner construction, burner bowl having a liquid fuel channel, a tube communicating and integrally united with and extending horizontally from the web of said channel, means affording a supply of liquid fuel, and a needle valve forming a horizontal continuation of said tube and having an end outlet connected to said tube and a side inlet above and connected to said means.

HERBERT M. REEVES. 55
